UNITED STATES PATENT OFFICE

157,011

CANDY CONTAINING MUSICAL TOY

Turney H. Stough, Jeannette, Pa.

Application March 22, 1948, Serial No. 145,268

Term of patent 3½ years

(Cl. D34—15)

To all whom it may concern:

Be it known that I, Turney H. Stough, a citizen of the United States of America, residing at Jeannette, in the county of Westmoreland and State of Pennsylvania, have invented a new, original, and ornamental Design for a Candy Containing Musical Toy, of which the following is a specification, reference being had to the accompanying drawing, forming part thereof.

In the drawing:

I claim:

The ornamental design for a candy containing musical toy, as shown.

TURNEY H. STOUGH.
